WIRE COIL CARRIER

Victor R. Beltram, Newton Falls, Ohio, assignor to The Falls Steel Tube & Manufacturing Company, Newton Falls, Ohio

Filed Sept. 5, 1962, Ser. No. 71,569

Term of patent 14 years

(Cl. D80—10)

FIGURE 1 is a perspective view of a wire coil carrier showing my new design,

FIGURE 2 is an enlarged top plan view thereof, and

FIGURE 3 is an enlarged side elevational view thereof.

I claim:

The ornamental design for a wire coil carrier, substantially as shown.
